UNITED STATES PATENT OFFICE

128,407

DESIGN FOR A HOMOGENIZER

Reinhard A. Yohpe, Battle Creek, Mich., assignor to Union Steam Pump Company, Battle Creek, Mich.

Application April 14, 1941, Serial No. 100,365

Term of patent 14 years

To all whom it may concern:

Be it known that I, Reinhard A. Yohpe, a citizen of the United States, residing at Battle Creek, in the county of Calhoun and State of Michigan, have invented a new, original, and ornamental Design for Homogenizer, of which the following is a specification, reference being had to the accompanying drawing, forming part thereof, in which:

Fig. 1 is a perspective view of a homogenizer embodying my new design, showing a portion of the top, the front and one side thereof, the front being at the left; and

Fig. 2 is a perspective view thereof, showing a portion of the top, the back and the other side of the homogenizer.

I claim:

The ornamental design for a homogenizer, substantially as shown.

REINHARD A. YOHPE.
